ASH TRANSFERRING DEVICE

Herbert R. Kerr, Red Bank, N. J.

Application June 1, 1940, Serial No. 338,446

1 Claim. (Cl. 214—1.1)

This invention relates to an improved device for transferring ashes or the like from the ash pit of a furnace or boiler to an ash can or similar receptacle.

5 The removal of ashes from an ash pit and their transference to an ash can or other receptacle is a burdensome task usually accompanied by considerable dust, dirt and disorder.

It is a prime object of the present invention to 10 facilitate this task and to eliminate or minimize the dust, dirt and disorder which accompanies it.

In carrying out my invention I provide a casing adapted to be placed on an ash can or similar 15 receptacle and having a closure through which a tray which previously received the ashes in the ash pit may be inserted. After the tray is in the casing the closure is closed and the tray is inverted so as to dump the contents into the ash 20 can. Since the casing and closure encases the entire top of the ash can it will be seen that the dust, dirt and disorder usually associated with the transfer or handling of ashes is eliminated.

In the accompanying drawings in which I 25 have shown one embodiment of my invention—

Fig. 1 is a perspective view of a device embodying my invention showing it applied to the top of an ash can;

Fig. 2 is a bracket used for supporting a removable tray in my device;

Fig. 3 is a cross sectional view partially fragmentary on the line 3—3 of Fig. 4;

Fig. 4 is a sectional view in the direction of the arrows on the line 4—4 of Fig. 3; and

Fig. 5 is a sectional plan view in the direction of the arrows on the line 5—5 of Fig. 3.

My improved ash transferring device comprises a casing 10 which may be of any desired 40 shape but is conveniently made of hexahedral shape as shown. The casing is placed on the top of an ash can 11 or similar receptacle and is open at the bottom as indicated at 12 so as to communicate with the interior of the ash can and is provided with an apron 14 having a circular depending flange which fits around the periphery of the top of the ash can. The interior of the casing is provided with an apron 15 which may be of any desired shape such as the 45 hexagonal shape illustrated and which is adapted to direct ashes from the casing into the ash can. As shown, the apron 15 is attached to the interior walls of the casing a short distance above the bottom thereof and tapers inwardly 50 to a point adjacent the top of the ash can to

provide a relatively restricted opening of smaller diameter than the diameter of the ash can.

I also provide inside the casing a bracket 16 which is adapted to receive a removable tray 17 on which the ashes are deposited in the ash pit 5 of the furnace or boiler. The construction of the bracket 16 may be varied but I have found that satisfactory results are obtained from the bracket illustrated which is formed of three connected angle irons with a connecting strip at the front. 10 Extending upwardly from the frame and forming part of the bracket are the retaining hooks 18 having their upper ends projecting inwardly so as to retain the movable tray on the bracket when it is in inverted position. The bracket is of 15 such a size as to conveniently accommodate the tray and the retaining hooks 18 preferably are formed so that the inwardly extending portions engage, or are no more than a short distance 20 above, the top of the walls of the tray. The bracket is supported in the casing by means of the shafts 19 and 20, the latter being formed with a crank or handle 21 which projects outside of the casing and permits the operator to manipulate the bracket so as to shift the tray between 25 upright position as shown in full lines in Figs. 3 and 4 and inverted position as shown in dotted lines in Fig. 4.

The front wall of the casing is provided with 30 an opening 22 through which the tray may be inserted and removed and the opening is provided with a closure 23 pivotally mounted as by means of the hinges 24 to the frame 25 that surrounds the opening. The closure is releasably 35 retained in closed position by means of the locking bolts 26 controlled by the external handles 27. The opening 22 is of such a size as to permit the tray to be conveniently inserted there-through.

40 So as normally to retain the bracket and tray in upright position I provide a locking shaft 28 which extends across the casing projecting there-through on both sides thereof in the manner shown. On the one side the locking shaft 28 projects into the path of movement of handle 21 so as to prevent the handle from pivoting upwardly. Inside the casing the shaft is positioned beneath the bracket 16 and it thus prevents the forward portion thereof from pivoting downwardly. In this way the bracket is effectively 45 held in fixed position under normal conditions.

When it is desired to invert the bracket so as 50 to dump the ashes from a tray positioned there-on into the ash can the locking shaft 28 may be 55 shifted to the right as viewed in Fig. 1 until it

is out of the path of movement of the handle 21. The handle 21 may then be raised upwardly so as to cause the bracket and tray to assume the position shown in dotted lines in Fig. 4. After 5 the ashes have been deposited in the ash can the tray and bracket may be returned to normal position by means of handle 21 and the locking shaft 28 may be shifted again into the path of movement of the handle to retain it in 10 that position.

The movement of locking shaft 28 is preferably limited in a predetermined manner by means of stops or lugs 29 fixed to the shaft on the inside of the casing as shown most clearly in 15 Fig. 5. The position of the lugs is such as to permit the shaft to shift into and out of the path of movement of handle 21 but so as to prevent the shaft from being accidentally released from the apertures in the casing.

20 It will be appreciated that my improved ash transferring device may be made of many different types of material such as galvanized iron or other metals. The tray 17 is preferably, for convenience, provided with handles as indicated at 30 so as to facilitate its insertion and removal from the ash pit and from the casing.

In using my device a tray similar to the tray 17 is first placed in the ash pit of the boiler or furnace from which the ashes are to be transferred so that the ashes are deposited therein. The casing 10 is placed on top of the ash can or other receptacle in the manner illustrated and when the tray 17 is full it is removed from the ash pit, inserted through the opening 35 22 and placed on the bracket 16. Closure 23 is then closed, locking shaft 28 is shifted out of the path of movement of the handle 21 and the bracket and tray are inverted by turning the handle. In this connection the shafts 19 and 20 40 may be positioned slightly off center so that the tray and bracket will invert automatically when the locking shaft is released. Due to the fact that the top of the ash can is entirely enclosed by the casing and closure substantially all of the dirt and dust arising when the ashes are dumped into the ash can will be confined inside of the ash can and casing. In this manner the tedious 45 and untidy task of shovelling ashes from an ash

pit into an ash can is eliminated and a simple, convenient, and tidy operation is substituted in its place.

It will be appreciated that while I have illustrated and described one embodiment of my invention that many changes may be made without departing from the spirit of the invention as set forth in the accompanying claim.

I claim:

An ash transferring device comprising a casing adapted to be applied to the top of an ash receptacle and having an opening at the bottom thereof communicating with the interior of the receptacle, a bracket pivotally mounted in the casing, a removable tray positioned on the bracket, a handle on the outside of the casing for shifting the bracket, said bracket being shiftable between upright position so that the ashes will be retained in the tray and inverted position so that the ashes are dumped from the tray into the ash receptacle, said casing being provided with an opening adjacent the bracket to permit the tray to be inserted and removed there-through, a closure for the opening shiftable between open position to permit the passage of the tray and closed position so that the top of the ash receptacle may be entirely enclosed by the casing and closure when the ashes are dumped from the tray into the ash receptacle and a releasable locking device for releasably retaining the bracket in upright position and consisting of a rod extending across the casing beneath the bracket and positioned between the pivotal mounting for the bracket and the opening in the casing so as to prevent the bracket from tilting forwardly towards the opening, one end of said rod projecting through the casing and the rod being shiftable within predetermined limits in the direction of its longitudinal axis so that the projecting end thereof can be shifted into the path of movement of the handle to prevent tilting of the bracket and out of the path of movement of the handle to permit tilting of the bracket in a direction away from the opening in the casing.

HERBERT R. KERR.
